UNITED STATES PATENT OFFICE

118,024

DESIGN FOR A STATUETTE OR SIMILAR ARTICLE

James C. Reynolds, Sheridan, Wyo.

Application May 15, 1939, Serial No. 85,008

Term of patent 14 years

To all whom it may concern:

Be it known that I, James C. Reynolds, a citizen of the United States, residing at Sheridan, in the county of Sheridan and State of Wyoming, have invented a new, original, and ornamental Design for a Statuette or Similar Article, of which the following is a specification, reference being had to the accompanying drawing, forming part thereof.

The figure is a perspective view of a statuette or similar article embodying my new design. The opposite side of the figure is similar to that shown. The design is adapted to serve as a mascot or emblem for a national political party.

I claim:

The ornamental design for a statuette or similar article, substantially as shown and described.

JAMES C. REYNOLDS.
